UNITED STATES PATENT OFFICE.

FREDERIC BARR, OF NEW YORK, N. Y.

ELECTRIC SWITCH.

1,097,209.

Specification of Letters Patent. Patented May 19, 1914.

Application filed December 16, 1912. Serial No. 736,921.

To all whom it may concern:

Be it known that I, FREDERIC BARR, a citizen of the United States of America, and residing at New York, in the county of Kings and State of New York, have invented new and useful Improvements in Electric Switches, of which the following is a specification.

My invention relates particularly to mechanism adapted to be operated by means of a pull cord or chain as it is commonly termed.

One object is to provide a simple and inexpensive mechanism in which the parts are housed and electrically insulated so as to avoid the possibility of short circuiting or grounding.

Another object is to provide a construction which can be readily assembled and readily wired or disassembled when desired.

Another object is to prevent or reduce arcing at the contacts in breaking the circuit.

In the form shown the pull switch mechanism is carried by an insulating block provided with flanges for spacing apart and insulating the terminals and switch contacts. The insulating block and the switch mechanism are housed in an insulating receptacle having an opening at the back to receive the mechanism and a passage through the front to serve as a guide for the chain. The preferred form of switch mechanism is of the rotary ratchet type in which a rotatable switch member having a plurality of spring arms is rotated step by step over one or more inclined stationary switch contacts and inclined insulating steps or faces. I have discovered that the arcing at the break can be practically eliminated so that the switch will run cold and without injury by simply forming spring contact arms in fan shape wider at the free ends so that when the rotary switch member is rotated and the circumferential length of the contact area decreases, the width of the contact area will increase to offset the decrease in length and thus maintain a sufficient area of contact to properly conduct the current without heating the contacts.

Figure 1, is a vertical section showing the mechanism in its normal position of rest. Fig. 2, is a rear view of the insulating base or receptacle portion. Fig. 3, is a rear view of the switch block and circuit terminals. Fig. 4, is an edge view and partial section of the same. Fig. 5, is a view of the

rear side of the switch carrying block. Fig. 6, is a view of the front side of the switch carrying block, the rotary and oscillating parts being removed. Fig. 7, is a face view of the rotary switch member and its insulating carrier. Fig. 8, is a detail view of one of the stationary switch contacts.

The receptacle or base 1 is preferably formed of insulating material such as porcelain and the switch carrying block 2 also of insulating material fits in a recess 3 in the rear of the base. The base has an opening 4 at the front serving as an insulating guide for the pull chain 5.

The inclined switch contacts 6 and 7 are arranged on opposite sides of the spindle 8 which is rigidly mounted in the block 2 by means of the slotted head 9 on one end of the spindle and the nut 10 screwed on to the spindle on the opposite face of the insulating block. Between the segmental switch contacts 6 and 7 are the inclined steps 11 and 12. The circuit terminals are formed

so as to have feet 13 and 14 secured in contact with the feet of the switch segments by screws 15 and 16. The side arms 17 and 18 are turned at substantially right angles to the feet 13 and 14 and the outer ends 19 and 20 are bent over into recesses 21 and 22 for the binding screws and the connection of the circuit wires. Narrow flanges of insulating material 23 and 24 protect parts of the edges of the circuit terminals and other flanges 25 and 26 protect other parts of the edges of the circuit terminals. A flange 27 extends around the front of the insulating block 2 above the switch contact segments 6 and 7. An insulating disk 28 is mounted to rotate on the spindle and has a central boss 29 and a peripheral flange 30 and serves as a carrier for the rotatable switch member 31 having the spring arms 32 and 33. A ratchet operating lever 34 is mounted on the spindle for turning the carrier 28 and spring contact member 31 step by step. A notched nut 35 is screwed on to the outer edge and a spring 36 is interposed between the nut 35 and the ratchet plate 34 so as to press the ratchet lever against the carrier and also tends to hold the parts in the position shown in Fig. 1 where the ratchet lever is pressed against the stop shoulder 37 of the insulating block. The flange 38 guards the end of the chain where it is attached to the operating lever 34 so as to prevent it from being accidentally dis-

engaged. A flange 39 over-stands the entire switch mechanism and serves to close the back of the opening 3. The base is also preferably provided with a groove 40, the 5 walls of which serve as a guard for the end of the spindle 8, the nut 5 and the spring 36 so as to prevent the chain from becoming entangled therewith. When the parts are assembled, the walls 41, 41 form one side of 10 the groove while the flange 27 forms the other side of the groove for the chain and the operating ratchet lever. When the parts are assembled it will be noted that the circuit terminals are inclosed between adjacent 15 walls and flanges of the insulating base and insulating block. The circuit may be traced through the parts 19, 17 and 15 of one circuit terminal to the switch contact 6, across the rotary switch member 31 to the switch 20 contact 7, and then through the parts 14, 18 and 20 of the other circuit terminal. The stationary switch contacts as before intimated are preferably inclined and resilient similar to the arms 32 and 33 of the 25 rotary switch member. In order to make these switch contacts and the switch member to wear and carry the necessary current, it is necessary to make them of rather thick material. When the material is thick it is 30 difficult to make it sufficiently resilient unless the arms are made comparatively narrow. This has been found to give insufficient area of contact just before the break. As a result the contacts heat up, and thus tend 35 to produce an arc at the break. I have found that this can be avoided by making the contact arms of fan shape, wider at the end. This insures sufficient area of contact even where the arms are stiff and do not bear 40 perfectly flat upon each other. By this construction while the ends of the arms are wide enough to carry the necessary current so as to prevent over heating and arcing, the bases of the arms are sufficiently narrow 45 to make the arms resilient even though of comparatively heavy material.

It will be noted that the insulating base and its interior recess, chain guiding passage and insulating walls is so designated that 50 it can be readily made of porcelain or a similar material by a simple die action. It will also be noted that the insulating block and its flanges and recesses necessary for the switch mechanism and circuit terminals is 55 so designed that it can be readily and cheaply made of porcelain by a simple and inexpensive die action. These are features of considerable importance in structures of this character in order that the device may be 60 made economically.

The circuit terminals are so constructed as to be readily assembled with the switch contacts and the insulating block. This question of assembling is also of importance 65 in devices of this character since it mate-

rially effects not only the cost of construction but accuracy of location of the parts as well.

What I claim is:

1. In an electric pull switch, an insulating support consisting of an insulating base provided with a recess in the rear thereof and an insulating block removably fitting in the said recess, said insulating support having terminal recesses in the rear face 70 thereof and the insulating base having a chain guide passage in the front thereof in line with the rear recess therein, switch mechanism carried by the insulating block including an operating chain passing out 75 through the chain guide passage at the front, circuit terminals extending rearwardly from the switch mechanism and terminating in angular ends seated in the terminal recesses in the rear face of the insulating support and binding screws engaged in said angular ends and thereby accessible at the rear face of the switch structure.

2. In a pull switch, the combination of an insulating base having a recess open at 80 the rear, a chain guide passage at the front, an insulating block removably fitting in said recess from the rear, switch mechanism carried by said block and including a spindle and an operating chain guided in said 85 chain guide passage, said insulating base having a groove to receive the end of the spindle, the walls of the groove acting to guard the spindle from said chain.

3. In a pull switch, an insulating base 100 having a recess open at the rear, a chain guide at the front, an insulating block removably fitting in said recess and held against movement when seated therein, switch mechanism carried by said block including an oscillating operating lever and a chain, said base and said relative stationary block having integral fixed walls forming 105 between them a guiding groove for the operating lever and the pull chain.

4. In a pull switch, an insulating base having a recess open at the rear and a chain guide open at the front, an insulating block removably fitting in said recess, switch mechanism carried by said block including 110 an operating chain guided in said chain guide, said block having an integral flange extending across in rear of the switch mechanism to thereby cover the switch mechanism at the rear and circuit terminals extending rearwardly from the switch mechanism to the rear side of the flange to be thereby accessible at the rear of the switch structure.

5. In a pull switch, an insulating base 125 having a recess open at the rear and a chain guide passage at the front, an insulating block removably fitting in said recess, switch mechanism carried by said block including switch contacts and an operating 130

chain, said insulating block having mutually coöperating insulating flanges forming an insulating chain guiding groove and preventing said chain from engaging with 5 said contacts.

6. In a pull switch, an insulating block, switch contacts carried thereby, a switch member adapted to connect said contacts, a pull chain for operating said switch member, circuit terminals connected to said switch contacts, each terminal consisting of a foot for engaging a contact, an arm extending at right angles to the foot and an outer end bent at right angles to said arm 10 and having a binding screw, said block having flanges guarding the opposite edges of said arms and having recesses for the binding screws.

7. In a pull switch, a receptacle having 20 a recess open at the rear and a chain guiding passage in the front, an insulating block removably fitting in said recess, and switch mechanism carried by said block at one face thereof including a pull chain extending 25 through said chain guide, circuit terminals in the edges of said insulating block extend-

ing rearwardly beyond the rear face of the block and binding screws engaged in the rearwardly extended portions of the circuit terminals at the rear side of the block. 30

8. In an electric switch, a fan-shaped inclined segmental switch contact narrow at the base of the incline and increasing in width to the free end and a rotatable switch member having inclined resilient arms of 35 fan-shape narrow at the base and increasing in width to the free ends, one of said resilient arms resting on said segmental switch contact with the broad end of said arm contacting with the narrow base of said 40 contact when the circuit is closed, the rotation of said switch member causing said arm to slide around on said segmental switch contact whereby the broad end of said arm is gradually brought into engagement with 45 the broad end of said contact just before the circuit is opened.
